UNITED STATES PATENT OFFICE.

CHARLES E. PAYNE, OF LAQUIN, PENNSYLVANIA.

DEVICE FOR GRINDING BAND-WHEELS.

No. 899,896.

Specification of Letters Patent. Patented Sept. 29, 1908.

Application filed December 18, 1907. Serial No. 407,071.

To all whom it may concern:

Be it known that I, CHARLES E. PAYNE, a citizen of the United States, residing at La-quin, in the county of Bradford and State of Pennsylvania, have invented certain new and useful Improvements in Devices for Grinding Band-Wheels; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to machines for grinding the faces of band wheels.

It has for its object to provide such a device in which the grinding tool can be progressively moved back and forth across the face of the wheel to be ground, also adjusted towards the wheel to compensate for wear of the tool, also set at different angles in relation to the face of the wheel, and which can be readily inverted and raised or lowered to grind either an upper or lower band wheel as may be desired.

To the accomplishment of the foregoing and such other objects as may hereinafter appear, the invention consists in features of construction and in combination of parts hereinafter particularly described and then sought to be clearly defined by the claims, reference being had to the accompanying drawings forming a part hereof, and in which

Figure 1 is a side elevation of the device, attached to the columns which support the band wheels; Fig. 2 a plan view of the same; Fig. 3 a vertical central section 40 through the device, showing one of the columns and in dotted lines an upper and lower band wheel; Fig. 4 a horizontal section on the line 4—4 of Fig. 3; and Fig. 5 a bottom view of the part of the device carrying the 45 grinding tool.

In the drawing the numeral 1 designates columns such as ordinarily employed for supporting band wheels 2 indicated by dotted lines in Fig. 3 of the drawing. To these columns are secured by bolts 4, or otherwise, the brackets 5 which have slots 6 in the portions which extend between the columns. These brackets sustain what for convenience will be designated a bed 7 which has a central

opening or slot 8 and a dovetailed tongue 9. 55
This bed is held to the brackets 5 by bolts 10
passing through the slots 6 of the brackets
and through slots 11 formed in the ends of the
bed at the top and bottom thereof. The
slots 6 in the brackets permit a vertical ad-
justment of the bed to bring it in proper re-
lation to the top band wheel, or to the bot-
tom band wheel as one or the other is to be
ground; and the slots 11 in the bed permit
the bed to be adjusted lengthwise, thus pro-
viding a vertical and a lateral adjustment of
the bed. 60 65

To the bed 7 is attached what for convenience will be designated as a carriage 12 which is formed with a dovetailed groove 13 70 which receives the dovetailed tongue of the bed, so that the carriage may slide along said tongue. The carriage is formed on one side with an internally threaded boss or nut 14 fitting in the slot 8 of the bed and receiving 75 a threaded rotatable shaft 15 fitted in suitable bearings 16 in the ends of the bed and provided at one end with a hand wheel 17 by which the shaft may be rotated so as to effect the carriage back and forth. The opposite 80 face of the carriage is formed with a stud or pindle 18 upon which is mounted a rotatable block 19 formed with semi-circular slots 20 through which pass bolts 21 whose threaded ends enter the carriage 12 so as to secure the 85 block to the carriage. This block has a dovetailed tongue 22 on one side upon which slides a two-part tool holder box 23, the members of said holder next to the block having a dovetailed groove receiving the tongue of the 90 block. The tool holder is moved along the tongue by a threaded rod 24 working in a threaded bore 25 in the block 19 and having a swiveled connection to a flange 26 in the tool holder so that by turning the rod by 95

means of a handle 27 the tool holder may be moved back and forth on the tongue of the block. The tool holder 23 comprises the two members 28, the meeting faces of which are formed with recesses forming a socket 29 in which fits the grinding tool 30 which is made of carborundum. The outer part of the holder has lugs or ears 31 which fit down over the sides of the inner members, and the two members are held together by suitable means, for instance by screws 32 which pass through one member into the other and by screws 33 which pass through the lugs 31 and into the

sides of the other member. The two members thus form a clamp which holds the carborundum grinding tool with sufficient friction to prevent it from slipping in its socket 5 and yet so as to permit it to be adjusted lengthwise as it wears. Such adjustment is effected by a screw 34 passing through a cap-plate 35 which may be held to the two-part box or tool holder so as to swing by a pivot- bolt 36, the other end being formed with a slot 37 so as to engage with a holding bolt 38. The inner end of the screw 34 has secured to it, or bears against a plate 39 which bears against the end of the carborundum stick or 10 tool. This backing plate also serves to prevent the tool from being pressed back in its socket when in working contact with the surface of the wheel being ground, and holds it to its work.

20 Sometimes it is desired to present the grinding tool at an angle to the face of the wheel being ground, for instance when it may be desired to slightly bevel or round the edge of the wheel, or for other purposes. This 25 can be effected by loosening the bolts 21 and turning the block 19 so as to present the grinding tool at the angle desired and holding it there by tightening the bolts.

In Fig. 3 of the drawing the device is shown 30 in position for grinding the upper band wheel. If it be desired to grind the lower wheel, the bolts 21 are withdrawn and the block 19 turned so as to carry the working end of the tool to face the lower wheel when 35 the bolts are replaced and the block locked in position. The bolts 10 may then be loosened and the bed 7 lowered on the brackets until the device is in position for grinding the lower wheel. It will thus be 40 observed that the device is always in position for grinding either wheel by merely adjusting the device which can be quickly and easily effected.

Between one wall of the dovetailed tongue 45 to the bed 7 and corresponding wall of the groove in the carriage 12, there is a filling plate 40 against which bears the screws 41, and between the dovetailed tongue 22 of the block 19 and the corresponding groove in the 50 tool holder box 23, on one side, is a filling plate 42 against which bears the screws 43.

I have illustrated and described with particularity the preferred construction of the various parts but it is obvious that changes 55 can be made therein and essential features of the invention be employed.

Having described my invention and set forth its merits what I claim is

1. The combination with the brackets 60 and the vertically adjustable bed supported thereon, of the reciprocating carriage mounted upon the bed, means for moving the carriage lengthwise of the bed, a tool holder carrying a grinding tool and adjustable trans-

revolute support for the tool holder, said tool holder and revolute support being sustained from one side of said bed, substantially as described.

2. The combination of the bed, the carriage 70 mounted upon the bed, means for moving the carriage lengthwise of the bed, a tool holder adjustable transversely to the travel of the carriage, a grinding tool carried by said holder, and means bearing against the rear of 75 the tool for projecting said tool beyond its holder, substantially as described.

3. The combination of the bed formed with a tongue and a longitudinally extending slot, a carriage formed with a groove to receive the tongue of the bed and having on one side an internally threaded nut fitting in the groove of the bed and on the opposite side a projecting stud, a feed screw passing through the nut, of the carriage, a grinding 80 tool-holder mounted upon the stud projecting from the opposite side of the carriage, and means for adjusting the tool holder transversely to the travel of the carriage, substantially as described. 85

4. The combination of the traveling carriage, the block invertible and revolute thereon, a grinding tool holder, a tongue and groove connection between the block and tool holder, and means for vertically adjusting the tool holder transversely to the travel of the carriage, substantially as described. 90

5. The combination with the traveling carriage, of a block revolvably mounted thereon, means for locking the block in various angularly disposed adjustments, a tool holder mounted upon said block to slide vertically 100 thereon transversely to the travel of the carriage, and means for sliding the tool holder to adjust it on the carriage, substantially as 105 described.

6. The combination with the traveling carriage, of the revolute tool holder adjustable transversely to the travel of the carriage and having a socket for a grinding tool, a grinding tool fitting in said socket, an adjustable plate in the socket for the end of the grinding tool to bear against, and means for moving said plate and grinding tool lengthwise of the socket in which the tool fits, substantially as 110 described. 115

7. The combination of the bed, the carriage mounted thereon, the invertible and revolute block having a pintle connection with the carriage and formed with arc slots, 120 bolts passing through said slots and entering the carriage, a tool holder having a tongue and groove connection with the block to permit it to be adjusted vertically and transversely to the travel of the carriage, and an adjusting screw connected with a part of the tool holder, and operating in said block for adjusting the tool holder, substantially as described.

8. The combination of the vertically ad- 125

justable bed, the carriage mounted to travel on said bed, and the grinding tool holder adjustable transversely to the travel of the carriage and adapted to be inverted so as to present the grinding tool in position to work from above or from beneath the bed, substantially as described.

In testimony whereof I affix my signature in presence of two witnesses.

CHARLES E. PAYNE.
